Primary Examiner — Joseph Kukella*Assistant Examiner* — Lavon M. Amerson(74) *Attorney, Agent, or Firm* — Quarles & Brady LLP; James J. Aquilina(57) **CLAIM**

The ornamental design for a gear alignment tool, as shown and described.

DESCRIPTION

FIG. 1 is an isometric view of a top, front, and left side of an ornamental design for a gear alignment tool;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The dashed broken lines are included for the purpose of illustrating portions of the gear alignment tool that form no part of the claimed design. The dashed-dotted broken line is included for the purpose of illustrating a boundary of the claim and forms no part of the claimed design.
